(57) **CLAIM**

The ornamental design for a digital borescope monitor, as shown and described.

DESCRIPTION

FIG. 1 is a perspective view of a digital borescope monitor, showing my new design;

FIG. 2 is a bottom plan view thereof;

FIG. 3 is a top plan view thereof;

FIG. 4 is front elevation view thereof;

FIG. 5 is rear elevation view thereof;

FIG. 6 is a right-side elevation view thereof; and,

FIG. 7 is a left-side elevation view thereof.

The broken lines shown in the drawings depict portions of the digital borescope monitor that form no part of the claimed design.
